[57] ABSTRACT

A flatiron having an air diffuser at the rear thereof for blowing air downwardly on work being pressed to cool it, an on-off valve for the air, and a switch at the forward end of the handle in position for operation by the thumb of the user's hand on the handle of the iron for operating the valve.

FLATIRON WITH WORK COOLING MEANS

BACKGROUND OF THE INVENTION

This invention relates to a flatiron with work cooling means, and more particularly to a flatiron with means for blowing air downwardly on work being pressed to cool it.

In pressing open seams of items of apparel made from high polyester content fabrics with a flatiron (usually an electric steam hand iron), difficulty has been encountered in that the fabric has a tendency to straighten out and close the seam once the flatiron has passed by due to slow cooling, and it has been found desirable to provide for rapid cooling of the fabric as it is pressed to set the fabric in the pressed-open position. This invention is directed toward providing a flatiron with means for effecting such cooling.

Reference may be made to the following patents as the closest known at the time of filing this application: U.S. Pat. No. 2,186,930, 2,362,590, 2,362,591, 2,402,575, 2,606,378, 2,629,949 and 2,639,520.

SUMMARY OF THE INVENTION

The principal object of the invention being as above noted, in accordance with this invention a flatiron (e.g. a conventional electric steam hand iron) is provided with an air diffuser mounted on the flatiron in position rearward of the rearward end of the body of the flatiron for blowing air downwardly on work being pressed with the iron to cool the work as the iron passes thereover, a flexible compressed air line extending from a source of compressed air to said diffuser, an on-off valve for controlling flow of air through said line to said diffuser, and means at the forward end of the handle operable by the thumb of the user's hand when on the handle for actuating the valve.

Other objects and features will be in part apparent and in part pointed out hereinafter.

BRIEF DESCRIPTION OF THE DRAWINGS

FIG. 1 is a side elevation of a flatiron equipped with cooling means of this invention;

FIG. 2 is a bottom plan of FIG. 1;

FIG. 3 is a rear end view of FIG. 1;

FIG. 4 is a horizontal section on line 4-4 of FIG. 1, and

FIG. 5 is a fragmentary front elevation on line 5-5 of FIG. 1.

Corresponding reference characters indicate corresponding parts throughout the several views of the drawings.

DESCRIPTION OF THE PREFERRED EMBODIMENT

Referring to the drawings, there is indicated at 1 a flatiron, shown as a conventional commercially available electric steam hand iron of the type disclosed in U.S. Pat. No. 3,412,492. This has the usual body 3 with a sole plate 5 having steam openings 7, and the usual handle 9. An air diffuser generally designated 11 is mounted on the flatiron 1 in position rearward of the rearward end of the body of the flatiron for blowing air downwardly on work being pressed with the iron rapidly to cool the work as the iron passes thereover. A flexible compressed air line 13 (adapted to permit the

hand manipulation of the iron) extends from a source of compressed air indicated at 15 to the diffuser. An on-off valve 17 is provided for controlling flow of air through the air line to the diffuser. Means indicated at 19 is provided at the forward end of the handle 9 operable by the thumb of the user's hand when on the handle for actuating the valve.

The valve 17 is a solenoid valve, and means 19 is a switch having an operating member constituted by a push button 21. This switch 29 is mounted on a bracket 23 secured at the forward end of the handle by means of the usual nut 25 on the usual bolt 27 extending through the handle with the button 21 at the left side of the handle (the left side as viewed in forward direction) and somewhat below the top of the handle whereby the button may be readily pushed down to close the switch by the thumb of the user's right hand when grasping the handle during pressing. Flexible conductors as indicated at 29 connect the switch and valve in series with an electric power source 31.

The air diffuser 11 comprises an air diffuser head 33 extending crosswise of the iron rearward of its rearward end and above the plane of the bottom of the iron. This head 33 is an elongate hollow member having an air exit slot 35 extending lengthwise thereof at its bottom 37. The head is preferably of curved form (see Fig. 3) with its bottom 37 containing the air exit slot 35 convex, i.e., curving slightly upward at its ends. The purpose of this is to have the air blow downwardly in a relatively wide band to cool the pressed-open margins of the fabric at the seam with the air at opposite sides of this band fanning outwardly (see the arrows in Fig. 3) to prevent air from blowing under the edges of the margins and lifting them up. A tubular stem 39 extends upwardly from the head at its center (the diffuser 11 thus resembling an inverted T), line 13 being connected to the upper end of this stem by a suitable coupling as indicated at 41. Air flows downwardly through the stem 39 to the head 33 and laterally outwardly in the head from the lower end of the stem. The head and stem may be formed as an integral hollow T-shaped element, the ends of the head being plugged as indicated at 43.

The diffuser 11 is mounted on the iron by means of a bracket 45 secured to the top of the body of the iron extending rearwardly beyond the rearward end of the iron, the stem 39 being mounted at the rearward end of the bracket and being adjustable up and down. The bracket 45 comprises a metal strip bent to V-shape having its ends 47 twisted to lie flat on top of the body of the iron and being secured thereto as by screws 49. The stem 39 is received in the apex of the V, which is rounded for this purpose as indicated at 51 in Fig. 4, and a clamp screw 53 is provided extending between the sides of the V immediately forward of the stem for drawing the sides together to clamp the stem in its adjusted position.

In the use of the iron to press open a seam, for example, the operator starts with the front point of the iron entered between the margins of the fabric in the seam to spread them apart and press them down. As she moves the iron forward, the operator presses down on the switch button 21 to close the switch, thereby energizing the solenoid of valve 17 to open the valve for flow of air to the head 33 and exit therefrom via slot 35 in a relatively wide band relatively rapidly to cool the

fabric immediately rearward of the iron as it is moved forward over the seam. This avoids the aforesaid straightening out of the fabric as might otherwise occur and sets it in the pressed-open position. When the operator finishes pressing a seam, she simply releases the button 21 to cut off the flow of air to conserve it until she starts pressing another seam.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. A flatiron having a body and a handle on the body, an air diffuser mounted on the flatiron in position rearward of the rearward end of the body of the flatiron for blowing air downwardly on work being pressed with the iron to cool the work as the iron passes thereover, a flexible compressed air line extending from a source of compressed air to said diffuser, an on-off valve for controlling flow of air through said line to said diffuser, and means at the forward end of the handle operable by the thumb of the user's hand when on the handle for actuating the valve.

2. A flatiron as set forth in claim 1 wherein the valve is a solenoid valve and said means at the forward end of the handle is a switch having an operating member positioned for engagement by the thumb.

3. A flatiron as set forth in claim 2 having flexible conductors between said switch and valve.

4. A flatiron as set forth in claim 2 wherein said diffuser comprises a diffuser head extending crosswise of the iron rearward of its rearward end above the bottom plane of the iron.

5. A flatiron as set forth in claim 4 wherein said head is an elongate hollow member having an air exit slot extending lengthwise thereof at its bottom.

10 6. A flatiron as set forth in claim 5 wherein said head is of curved form with its bottom containing the air exit slot convex.

7. A flatiron as set forth in claim 6 having a tubular stem extending upwardly from the center of the head, 15 said flexible air line being connected to the upper end of the stem, air flowing downwardly through the stem to the head.

8. A flatiron as set forth in claim 7 wherein the diffuser is mounted on the iron by means of a bracket 20 secured to the top of the body of the iron extending rearwardly beyond the rearward end of the iron, the stem being mounted at the rearward end of said bracket and being adjustable up and down.

9. A flatiron as set forth in claim 8 wherein the 25 bracket comprises a metal strip bent to V shape and having its ends twisted to lie flat on top of the body of the iron and being secured thereto, the stem being received in the apex of the V, and wherein a clamp screw is provided between the sides of the V forward of 30 the stem for drawing said sides together to clamp the stem.
